UNITED STATES PATENT OFFICE.

ALEXANDER CAMERON, JR., OF RICHMOND, VIRGINIA.

DESIGN FOR A BOX OR CAN.

SPECIFICATION forming part of Design No. 27,458, dated August 3, 1897.

Application filed June 26, 1897. Serial No. 642,544. Term of patent 7 years.

To all whom it may concern.

Be it known that I, ALEXANDER CAMERON, Jr., a citizen of the United States, residing at Richmond, in the county of Henrico and State 5 of Virginia, have invented and produced a new and original Design for Boxes or Cans; and I do hereby declare the following to be a full, clear, and exact description of the same, reference being had to the accompanying 10 drawing, forming a part thereof.

My invention relates to a design for the ornamentation of boxes or cans, as will be hereinafter described, and illustrated in the accompanying drawing.

15 The figure is a perspective view of the box or can, showing my design thereon.

As shown in the drawing, the leading or material features of my design consist of a rectangular space or outline A, having a band 20 or panel B extending diagonally across the rectangular space and forming two triangular

panels b b' above and below the diagonal band and having a centrally-arranged circle a and a smaller circle a' a² on each side of the centrally-arranged circle. Above the circles are 25 two small scrolls or panels C C, and below the circles is a broad scroll D, extending through the lower triangular panel and the diagonal band.

Having now described my invention, what 30 I claim as new, and desire to secure by Letters Patent, is—

The design for the ornamentation of a box or can, substantially as herein shown and described.

35

In testimony whereof I hereunto affix my signature in presence of two witnesses.

ALEXANDER CAMERON, JR.
